CLAMP FOR A MANNEQUIN HEAD

William E. Anson, Warren, Mich., assignor to Michigan Wig Products Company, Inc., Grosse Pointe Farms, Mich., a corporation of Michigan

Filed Mar. 20, 1967, Ser. No. 6,303

Term of patent 7 years

(Cl. D54—1)

I claim:

The ornamental design for a clamp for a mannequin head, substantially as shown.
